KEY HOLDER

Filed Nov. 29, 1949

UNITED STATES PATENT OFFICE

2,608,851

KEY HOLDER

Samuel Leff, Brooklyn, N. Y.

Application November 29, 1949, Serial No. 129,965

9 Claims. (Cl. 70—456)

1

This invention relates to key holders. More particularly my invention pertains to key holders of the type including a spring which is compressed when a key is urged to retracted position within a housing, so as to store energy which subsequently is released to snap the key to an extended position.

It is an object of my invention to provide a key holder of the character described which is of such construction that the key automatically is latched in retracted position, i. e. latched, without manipulation of any parts.

It is another object of my invention to provide a key holder of the character described which is of particularly simple construction and is positive and reliable in operation.

Other objects of my invention will in part be obvious and in part will be pointed out hereinafter.

My invention accordingly consists in the features of construction, combinations of elements and arrangements of parts which will be exemplified in the device hereinafter described and of which the scope of application will be indicated in the appended claims.

In the accompanying drawings in which is shown one of the various possible embodiments of my invention,

Fig. 1 is a plan view of a key holder constructed in accordance with my invention, the key being illustrated in retracted position;

Fig. 2 is a side view thereof;

Fig. 3 is a sectional view through the key holder, the same being taken substantially along the line 3—3 of Fig. 2;

Figs. 4, 5 and 6 are sectional views taken substantially along the lines 4—4, 5—5 and 6—6, respectively, of Fig. 3;

Fig. 7 is a view similar to Fig. 3 but with the key shown in extended position; and

Fig. 8 is an exploded view showing the inner surfaces of the two halves of the key holder housing.

Referring now in detail to the drawings, the reference numeral 10 denotes a key holder embodying my invention and comprising a housing 12, a key post 14, a pair of springs 16, 18 and a bridle 20.

The housing 12 preferably is made in two halves 22, 24 (Fig. 8) which are mirror images of one another so that only one half 22 need be described. The corresponding parts of the other half 24 are denoted by the same reference numerals primed.

The housing half 22 is fabricated from some

2

inexpensive material and in accordance with the preferred form of my invention is molded from a plastic material, for example, any one of the well known synthetic plastics such as cellulose acetate, ethyl cellulose, ethyl cellulose butyrate, an acrylic resin, styrene, a phenol formaldehyde resin or a urea formaldehyde resin. Due to its simple shape and non-critical dimensions and to the absence of above normal temperatures during its ordinary use, I have found it most convenient to make the housing halves from a thermoplastic resin by injection molding.

Said housing half 22 constitutes a thin wall 26 of generally oblong shape whose outside surface 15 may, as illustrated, be substantially flat, although, if desired, any suitable ornamentation therefor can be included. The wall is provided with a through slot 28 disposed approximately midway between the two longitudinal edges of 20 the wall. The side edges 30, 32 and inner edge 34 of the housing half 22 are provided with a rail or flange 36 which, in conjunction with the flange 36' on the other half 24, cooperate to define a thin space between the two walls 26, 25 26' when the housing halves are registered and abutted and the rails face one another.

One side edge, for example the edge 30, is fashioned with a notch or indentation 38 through which the tang 40 of a key K is adapted to project when the key is retracted within the key holder in a fashion later to be described. In order that the tang of the key may be visible and accessible through the indentation, the flanges 36, 36' are interrupted at this point.

35 The slot 28 terminates at an outer end 42, located on the longitudinal center line on the housing half 22. The inner end 44 of said slot, however, is differently arranged, running into a laterally extending branch 46 which slopes at least 40 to a slight extent in a direction back toward the outer end of the housing, this branch therefore in effect imparting a hook formation to the inner end of the slot on a side adjacent the notch 38. The tip of this laterally extending branch is 45 transversely offset from the longitudinal and central axis of the long straight portion of the slot by at least slightly more than the width of the slot. As a result of the foregoing construction, the outer edge 48 of the branch 46 makes 50 an angle of less than 90° with the adjacent edge 49 of the slot 28, and an element slideable in the slot can by proper manipulation have more than one half thereof received in the branch.

On the inside surface of the housing means is 55 provided to locate the springs 16, 18. These

springs constitute elongated spiral coil compression springs and the locating means therefor includes a pair of channels 50, 52. Said channels are located on opposite sides of the slot 28 and run substantially the full length of the halves 22, 24, terminating slightly short of the two ends of the housing. The channel 52 which is adjacent the indentation 38 is closer to the inner offset end 44 of the slot 28 than is the other channel 50. The inner ends of the channels 50, 52 constitute seats for the inner ends of the springs. The top ends of the channels are defined by a slightly raised flat 54 whose height is intermediate the height of the wall 26 and the flange 36. The heights of the ribs 56 constituting the sides of the channels 50, 52 are such that the space between the ribs 56, 56' is slightly in excess of the thickness of the key K thereby permitting the tang of the key to slide on and between said ribs.

The key post 14 comprises two parts, each part containing one half of a rapidly attachable and detachable interengaging means. Thus said post, as shown, includes a stub spindle 58 which desirably is of circular cross-sectional configuration having a diameter such that the spindle makes a sliding fit with the slots 28, 28' and the reaches 46, 46'. Said spindle is provided with a head 60 at its outside end and at its inside end has a tapped bore 62 into which a headed screw 64 is threadable. The length of the spindle between its head 60 and the head of the screw is slightly in excess of the thickness of the housing. Thus the post 14 is freely slideable along the length of the slots 28, 28' and can be shifted into the offset reaches 46, 46'.

The bridle 20 includes an elongated shank 66 which is slideable in a cavity defined by opposed indentations 68, 68' lying between the spring locating channels 50, 52 and 50', 52'. The opposite ends of the shank are formed into shoes 70, 72 which have cross-sections substantially similar to the cross-sections of the springs 16, 18 and therefore are adapted to ride in the channels 50, 52. The shank and heads of the bridle fit loosely enough in their channels to permit a slight tilting movement of the bridle, the purpose whereof will be pointed out hereinafter. The bridle is located at the outer ends of the springs between said springs and the key post 14.

The edge 74 of the slot 28 where it runs into the inner end 44 of the slot is inclined toward the edge 30 of the housing having the indentation 38, this inclination being quite gradual and commencing at a point *a* above the inner end of the edge 49. Said edge 74 at its innermost point *b* is located closer to the edge 30 of the housing than either the edge 49 of the slot or the point *c* which joins the edges 48, 49.

The purpose of providing the inner end 44 of the slot with a configuration such as just described is to obtain an automatic latching action when the key is moved to retracted position. At such time, due to the gradual inclination of the edge 74, the key post does not tend to halt its inward movement as it is urged to retracted position by manual pressure on its tip 76. When the key post reaches the innermost point *b*, the key is released. It then is nearer to the channel 52 adjacent the indentation 38 than it is to the channel 50 remote from said indentation. As a result, the resultant of the forces exerted by the springs on the bridle is located at a point on the side of the key post away from the reach 46 and, accordingly, the bridle 66 will be slightly tilted in a direction toward said reach. Therefore, when

pressure on the key is released the bridle will, in addition to urging the key post upwardly, tend to press it sideways toward the indentation 38, this action resulting in insuring motion of the key post into the hook, i. e. against the edge 48.

To release the key, a finger is pressed against the portion of a key tang 40 exposed in the indentation 38. This will force the key post out from under the point *c* so that when manual pressure is removed the springs 16, 18 will snap the key to its projected position.

Inasmuch as the walls 26, 26' are comparatively thin (in the order of $\frac{1}{2}$ of an inch) the outer ends of said walls are somewhat flexible so that the pressure with which a person grasps the holder when the key is turned suffices to flex the outer ends of said walls inwardly enough for the flats 54, 54', and tips of the ribs 56, 56' which are level with the flats, firmly to engage the shank of the key.

One of the housing halves, e. g. the half 22, is fashioned with sockets 78 in the flange 36 and the other half with pins 80 designed to be received in said sockets so that the halves may be properly registered. The halves can be held together in any suitable manner, for example by cementing the halves together or by autogenous sealing the same.

Each half is formed with a through opening 82 adjacent its inner edge 34, thus providing an aperture for the reception of a key chain.

To assemble the key holder, the springs 16, 18 are placed in the channels 50, 52 of one of the halves and the bridle located above the outer ends of the springs with its ends 70, 72 disposed in said channels. Then the other half of the housing is placed over the first housing half and the two halves joined. Thereafter the spindle 58 is introduced into the slot 28 at the end 42 from one side of the housing and the screw 64 introduced into the slot from the opposite side of the housing, the two parts of the post being threadably engaged.

When it is desired to mount a key, the two parts of the post are disengaged and the key tang slipped through the outer open end of the housing between the flats 54, 54'. The central opening 84 of the key tang is registered with the slots 28, 28' near the outer ends 42, 42' thereof. Then the parts of the post are reassembled with the spindle 58 extending through said central opening. At this time the various parts are in the position illustrated in Fig. 7.

The present application is a continuation-in-part of my copending application for key holders filed December 30, 1948, Serial No. 68,300, now Patent No. 2,490,396 issued December 6, 1949.

It thus will be seen that I have provided a device which achieves all the objects of my invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described my invention, I claim

70 as new and desire to secure by Letters Patent:

1. A key holder consisting of a housing comprising a pair of parallel spaced walls and means joining the side and inner edges of said walls to define an enclosed thin space, said housing being elongated in a direction from the outer end to

the inner end thereof, said walls having a pair of registered longitudinally extending slots, a post having heads on both ends thereof, said post being slideable in said slots, a pair of elongated longitudinally extending compression coil springs within said housing, means to locate said springs on opposite sides of said slots, a bridle in said housing, means to guide said bridle for movement longitudinally of said housing, said bridle being positioned on the outer ends of said springs whereby said springs urge the bridle toward the outer end of the housing, said outer end of the housing being open, said post being disposed in the slots above the bridle, the inner ends of said slots having reaches extending laterally therefrom and in which the post is slideable, said reaches extending laterally a distance not less than half the width of the post and sloping back in the direction of the outer end of the housing, the tips of said reaches being closer to the spring in the direction the reaches extend than to the other spring.

2. A key holder consisting of a housing comprising a pair of parallel spaced walls and means joining the side and inner edges of said walls to define an enclosed thin space, said housing being elongated in a direction from the outer end to the inner end thereof, said walls having a pair of registered longitudinally extending slots, a post, said post being slideable in said slots, a pair of elongated longitudinally extending compression coil springs within said housing, means to locate said springs on opposite sides of said slots, a bridle in said housing, means to guide said bridle for movement longitudinally of said housing, said bridle being positioned on the outer ends of said springs whereby said springs urge the bridle toward the outer end of the housing, said outer end of the housing being open, said post being disposed in the slots above the bridle, the inner ends of said slots having reaches extending laterally therefrom and in which the post is slideable, said reaches extending laterally a distance not less than half the width of the post, the tips of said reaches being closer to the spring in the direction the reaches extend than to the other spring.

3. A key holder consisting of a housing comprising a pair of parallel spaced walls and means joining the side and inner edges of said walls to define an enclosed thin space, said housing being elongated in a direction from the outer end to the inner end thereof, said walls having a pair of registered longitudinally extending slots, a post, said post being slideable in said slots, a pair of elongated longitudinally extending compression coil springs within said housing, means to locate said springs on opposite sides of said slots, a bridle in said housing, means to guide said bridle for movement longitudinally of said housing, said bridle being positioned on the outer ends of said springs whereby said springs urge the bridle toward the outer end of the housing, said outer end of the housing being open, said post being disposed in the slots above the bridle, the inner ends of said slots having reaches extending laterally therefrom and in which the post is slideable, the tips of said reaches being closer to the spring in the direction the reaches extend than to the other spring.

4. A key holder consisting of a housing comprising a pair of parallel spaced walls and means joining the side and inner edges of said walls to define an enclosed thin space, said housing being elongated in a direction from the outer end to

the inner end thereof, said walls having a pair of registered longitudinally extending slots, a post, said post being slideable in said slots, the inner ends of said slots having reaches extending laterally therefrom and in which the post is slideable, said reaches extending laterally a distance not less than one half the width of the post, a bridle within said housing beneath said post, means loosely to guide said bridle for movement longitudinally of said housing, and means within said housing for resiliently urging said bridle toward the open end of the housing, said means exerting a force on the bridle at a point which is on the side of the post away from the reaches when the post is at the inner ends of the slots.

5. A key holder consisting of a housing comprising a pair of parallel spaced walls and means joining the side and inner edges of said walls to define an enclosed thin space, said housing being elongated in a direction from the outer end to the inner end thereof, said walls having a pair of registered longitudinally extending slots, a post, said post being slideable in said slots, a pair of elongated longitudinally extending compression coil springs within said housing, channels in said housing locating said springs on opposite sides of said slots, a bridle in said housing, said bridle having elements slideable in said channels whereby said bridle is guided for movement longitudinally of said housing, said bridle being positioned on the outer ends of said springs, whereby said springs urge the bridle toward the outer end of the housing, said outer end of the housing being open, said post being disposed in the slots above the bridle, the inner ends of said slots having reaches extending laterally therefrom and in which the post is slideable, said reaches extending laterally a distance not less than half the width of the post and sloping back in the direction of the outer end of the housing, the tips of said reaches being closer to the spring in the direction the reaches extend than to the other spring.

6. A key holder consisting of a housing comprising a pair of parallel spaced walls and means joining the side and inner edges of said walls to define an enclosed thin space, said housing being elongated in a direction from the outer end to the inner end thereof, said walls having a pair of registered longitudinally extending slots, a post, said post being slideable in said slots, a pair of elongated longitudinally extending compression coil springs within said housing, channels in said housing locating said springs on opposite sides of said slots, a bridle in said housing, said bridle having elements slideable in said channels whereby said bridle is guided for movement longitudinally of said housing, said bridle being positioned on the outer ends of said springs, whereby said springs urge the bridle toward the outer end of the housing, said outer end of the housing being open, said post being disposed in the slots above the bridle, the inner ends of said slots sloping gradually into reaches extending laterally therefrom and in which the post is slideable, said reaches extending laterally a distance not less than half the width of the post and sloping back in the direction of the outer end of the housing, the tips of said reaches being closer to the spring in the direction the reaches extend than to the other spring.

7. A key holder consisting of a housing comprising a pair of parallel spaced walls and means joining the side and inner edges of said walls to define an enclosed thin space, said housing being elongated in a direction from the outer end

to the inner end thereof, said walls having a pair of registered longitudinally extending slots, a post, said post being slideable in said slots, a pair of elongated longitudinally extending compression coil springs within said housing, means to locate said springs on opposite sides of said slots, a bridle in said housing, means to guide said bridle for movement longitudinally of said housing, said bridle being positioned on the outer ends of said springs whereby said springs urge the bridle toward the outer end of the housing, said outer end of the housing being open, said post being disposed in the slots above the bridle, the inner ends of said slots having reaches extending laterally therefrom and in which the post is slideable, the tips of said reaches being closer to the spring in the direction the reaches extend than to the other spring, said housing having an open indentation on the side thereof toward which the reaches extend, the tang of a key carried by the post being visible through said indentation and being accessible therethrough when the post is located in said reaches.

8. A key holder consisting of a housing comprising a pair of parallel spaced walls and means joining the side and inner edges of said walls to define an enclosed thin space, said housing being elongated in a direction from the outer end to the inner end thereof, said walls having a pair of registered longitudinally extending slots, a post having heads on both ends thereof, said post being slideable in said slots, a pair of elongated longitudinally extending compression coil springs within said housing, means to locate said springs on opposite sides of said slots, a bridle in said housing, means to guide said bridle for movement longitudinally of said housing, said bridle being positioned on the outer ends of said springs whereby said springs urge the bridle toward the outer end of the housing, said outer end of the housing being open, said post being disposed in the slots above the bridle, the inner ends of said slots having reaches extending laterally therefrom and in which the post is slideable, said reaches extending laterally a distance not less than half the width of the post and sloping back in the direction of the outer end of the housing, the tips of said reaches being closer to the spring in the direction the reaches extend than to the other spring, said housing having an open indentation

tation on the side thereof toward which the reaches extend, the tang of a key carried by the post being visible through said indentation and being accessible therethrough when the post is located in said reaches.

5 9. A key holder consisting of a housing comprising a pair of parallel spaced walls and means joining the side and inner edges of said walls to define an enclosed thin space, said housing being elongated in a direction from the outer end to the inner end thereof, said walls having a pair of registered longitudinally extending slots, a post, said post being slideable in said slots, a pair of elongated longitudinally extending compression coil springs within said housing, channels in said housing locating said springs on opposite sides of said slots, a bridle in said housing, said bridle having elements slideable in said channels whereby said bridle is guided for movement longitudinally of said housing, said bridle being positioned on the outer ends of said springs, whereby said springs urge the bridle toward the outer end of the housing, said outer end of the housing being open, said post being disposed in the slots above the bridle, the inner ends of said slots sloping gradually into reaches extending laterally therefrom and in which the post is slideable, said reaches extending laterally a distance not less than half the width of the post and sloping back in the direction of the outer end of the housing, the tips of said reaches being closer to the spring in the direction the reaches extend than to the other spring, said housing having an open indentation on the side thereof toward which the reaches extend, the tang of a key carried by the post being visible through said indentation and being accessible therethrough when the post is located in said reaches.
